CLAIM

The ornamental design for a dolly wheel fender, as shown and described.

DESCRIPTION

The dolly wheel fender is characterized by a single side support with a cantilevered axle shaft.

FIG. 1 is a side elevation view of a dolly wheel fender showing my new design; the broken lines are for illustrative purposes only and form no part of the claimed design;

FIG. 2 is a front elevation view thereof;

FIG. 3 is a top view thereof; and,

FIG. 4 is a perspective view thereof.
